UNITED STATES PATENT OFFICE

RUDOLPH W. RINGENBERG, OF WATERBURY, CONNECTICUT, ASSIGNOR TO SCOVILL MANUFACTURING COMPANY, OF WATERBURY, CONNECTICUT, A CORPORATION OF CONNECTICUT

SIFTER TOP FOR POWDER CANS

Application filed December 6, 1927. Serial No. 238,031.

This invention relates to certain improvements in sifter tops for powder cans and the like.

In packaging certain toilet powders, as for instance stearate of zinc, it is necessary that the sifter top used for dispensing such powder should be so constructed that it will automatically close and will remain closed when not in use. It is further desirable in this class of tops that the parts should be few in number, and so arranged that they can be quickly assembled, as such tops to be commercially practical must be very cheaply produced.

It is the special object of the present invention to produce a sifter top which will automatically close when not in use, and which shall be of cheap construction, in addition to being substantially proof against powder leakage.

A further object of the present invention is to produce such a construction in which the controlling means for the dispensing orifices may be manipulated with one hand, and which shall be of neat and attractive appearance.

With these and other objects not specifically referred to in view, the invention consists in certain novel parts, arrangements and combinations which will be described in connection with the accompanying drawings and the novel features pointed out in the claims hereunto annexed.

In these drawings,—

Figure 1 is a top plan view, partly broken away, showing the improved sifter top with the dispensing orifices closed;

Figure 2 is a similar view showing the orifices open, and

Figure 3 is a sectional view of the operating parts of the top, the view being taken on line 3—3 of Figure 2.

Referring now to these drawings, the improved sifter top is shown as employed with a metal container in the form of an oval or elliptical tin can, but it will be understood that the top, as to certain of its features, may be used with other containers and with containers of any desired or suitable shape, and the invention is not therefore to be restricted to the particular container shown.

Referring, however, to the construction chosen to illustrate the invention, there is provided a container of light metal 1, which is provided with a neck 2. Where a metal container such as 1 is used, the neck 2 can form a part of the sifter device. It will be understood, however, that if desired the sifter device may be made entirely separate and assembled with containers other than metal containers, as, for instance, a glass jar, but such a construction is not illustrated, as unnecessary for an understanding of the invention. The neck 2 is formed, in the particular construction illustrated, with a top 3 and is provided centrally with dispensing orifices 4. The top 3 of the neck is formed with a depression 5 to receive a controller plate 6, of light metal, and a spring member 7. The controller 6 is in the form of a thin metal plate having distributing openings 8, and the spring 7 and the controller plate 6 are of a thickness to just fill the depression, which is closed by a cap 9, the wall 10 of which is spun or bent against the wall of the neck 2 so as to have a close friction fit and effectually prevent leakage of powder therebetween. The controller plate 6 is held so as to have frictional engagement with the top 3 and with the under side of the cap 9, and this cap 9 is provided with powder apertures, indicated at 11, this arrangement of the parts preventing leakage of powder until the controller plate is manipulated to bring the dispensing orifices of all three parts into alignment.

In accordance with the invention, means are provided for so manipulating the plate, and these means will be such that the plate will be returned to closed position and held in closed position when the can is not being used. Furthermore, these manipulating means will preferably be such that they can be operated with one hand. While the particular arrangement of the parts may be somewhat varied, this movement of the plate is effected by a rotary movement, and the rotary movement of the plate is such as to put the spring under tension, this spring returning the plate to normal or non-dispensing position when the spring is released. For sim-

plicity of construction, the spring is also formed with a handle, by which the parts are manipulated, and the movement of the handle effects the rotation of the plate. In 5 the construction shown, therefore, the plate 6 is in effect a cam plate and is provided with a nose 12 which engages in a notch 13 in one arm 14 of a forked spring, the other arm 15 of which engages the plate on the side opposite the notch. The arms of this spring are joined together to form an operating handle 16 which projects through a guide slot 17 formed in the wall 10 of the cap 9, before referred to.

15 It will be seen that by pushing the handle 16 toward the left, as shown in Figure 1, the plate 6 will be rotated in a clockwise direction and the arms of the spring will be put under tension. When now pressure is released on the handle 16, the spring will contract and automatically rotate the plate in a counter-clockwise direction and close the distributing orifices. The plate is held in position in any suitable manner, as on a pivot 18 formed 20 in the cap piece. It will be observed that the only parts necessary for the operation of the device is the cam plate 6, the spring and the pivot 18 for the plate. Thus a very simple 25 and economical structure has been provided, one which is practically leak-proof when in non-use, and one which can be readily and cheaply assembled.

30 While the invention has been described in its preferred form, it will be understood that 35 certain changes and variations may be made in the form and arrangement of the various parts without departing from the invention as defined in the appended claims.

What I claim is:

- 40 1. In a sifter top, upper and lower members provided with distributing orifices, a rotary cam plate between the members provided with distributing orifices, a spring means engaging the plate on opposite sides, and a pusher having a straight line movement connected with a spring and acting to rotate the plate to dispensing position, the spring returning the plate to closing position on the release of the pusher.
- 45 2. In a sifter top, upper and lower members provided with distributing orifices, a depression in one of the members, a rotary cam plate pivoted in the depression and having distributing orifices, a spring yoke engaging the plate on opposite sides, and a pusher having a straight line movement connected with the spring and acting to rotate the plate to dispensing position, the spring returning the plate to closing position on the release of the pusher.
- 50 3. In a sifter top, upper and lower members provided with distributing orifices, a depression in one of the members, a rotary cam plate confined in the depression and having distributing orifices, a projection on the plate,
- 55
- 60
- 65

a spring arm having a notch engaged by the projection, a second spring arm engaging the plate on the opposite side of the arms, and a pusher having a straight line movement connected with one of the arms for rotating the plate, the other arm acting to return the plate on release of the pusher.

In testimony whereof, I have hereunto set my hand.

RUDOLPH W. RINGENBERG.
